Term of patent 14 years

(Cl. D54—4)

FIG. 1

FIG. 2

FIG. 3

FIG. 4

FIG. 5

Fig. 1 is a side elevational view of a drill embodying my new design;

Fig. 2 is a top plan view of the same;

Fig. 3 is a side elevational view of said drill, showing the side thereof opposite to the side shown in Fig. 1;

Fig. 4 is a front elevational view of said drill; and

Fig. 5 is a rear elevational view thereof.

The handle and cord, shown in broken lines, have been broken away in Figs. 4 and 5 for convenience of illustration.

The dominant features of the design are shown in full lines in the drawings.

I claim:

The ornamental design for a drill, substantially as shown and described.
